CLAIM

The ornamental design for a wine aerator, as shown and described.

DESCRIPTION

FIG. 1 is a perspective top view of a wine aerator.

FIG. 2 is side view of the wine aerator of FIG. 1.

FIG. 3 is a side view of the wine aerator of FIG. 1 rotated 90 degrees about the axis of the aerator from the view shown in FIG. 2.

FIG. 4 a side view of the wine aerator of FIG. 1 rotated 90 degrees about the axis of the aerator from the view shown in FIG. 3.

FIG. 5 a side view of the wine aerator of FIG. 1 rotated 90 degrees about the axis of the aerator from the view shown in FIG. 4.

FIG. 6 is a top view of the wine aerator of FIG. 1; and,

FIG. 7 is a bottom view of the wine aerator of FIG. 1.

The broken lines in the drawings are included for the purpose of illustration and form no part of the claimed design.

1 Claim, 6 Drawing Sheets
